UNITED STATES PATENT OFFICE.

JOHN WESLEY POPE, OF MEMPHIS, TENNESSEE.

FARE-COLLECTING DEVICE.

Application filed October 2, 1919. Serial No. 327,896.

To all whom it may concern:

Be it known that I, JOHN WESLEY POPE, a citizen of the United States, and a resident of Memphis, in the county of Shelby and State of Tennessee, have invented certain new and useful Improvements in Fare-Collecting Devices, of which the following is a specification.

My invention is an improvement in fare collecting devices for use in one-man street car operating systems, and has for its object to provide a device of the character specified especially adapted for use in such systems with the car stop annunciator and ticket time stamping device forming the subject matter of my co-pending applications, wherein a turnstile is provided, normally locked and controlled to unlock by the insertion of the proper coin or coins in the collector.

In the drawings:

Figure 1 is a diagrammatic view of a street car provided with the collectors;

Figure 2 is a top plan view of the turnstile shaft locking mechanism with parts in section;

Figure 3 is a vertical section through the coin controlled mechanism;

Figure 4 is a section at right angles to Figure 3;

Figure 5 is a detail view of the mutilated gears;

Figure 6 is a side view of a plunger;

Figure 7 is a front view;

Figure 8 is a section on the line 8—8 of Figure 10;

Figure 9 is a front view of the counting dial;

Figure 10 is a vertical section of the disk counter.

The present embodiment of the invention is shown in connection with a street car 1 of any approved type, having the platform 2 at its ends, over which the passenger must pass to enter the car. On each platform is arranged a turnstile 3, through which the passenger must enter to gain the interior of the car, and these stiles are normally locked against egress, but move freely to permit ingress, the lock being released by the insertion of the proper coin in the coin controlled mechanism. The shaft 4 of the turnstile carries a ratchet ring 5 having teeth which are engaged by a pawl 6 to

prevent rotation of the turnstile in a direction to permit the passenger to depart. The pawl 6 and ratchet ring 5 constitute lock mechanism for the turnstile. This pawl is controlled to released position by a pawl or master bar 7 mounted to move longitudinally, and pivoted at one end to the pawl. The other end of the lever extends longitudinally of the fare box 8. This fare box has five chutes 9, 10, 11, 12 and 13, the said chutes being of a size to permit the passage of coins of different denominations, as, for instance 5¢, 10¢, 25¢, 50¢ and \$1.00 and ticket transfer disks.

Adjacent to each of these chutes there is mounted a plunger rod 14, each rod extending through the top of the case and having a head 15 above the case. The rods are mounted to slide in horizontal partitions 16 and 17, and each rod is normally spring pressed upward by a coil spring 18, encircling the rod between the partition 17 and a stop 19 on the rod. Each rod is normally locked against downward movement by means of a locking lever 20. Each of these levers is pivoted on the wall of the adjacent chute, and has at one end a lug 21, extending into the chute and adapted to be engaged by an entering coin, to swing the upper end of the lever outward. The lower end of each lever has a catch lug 22 which is adapted to engage a catch on the adjacent rod, to normally hold the rod lifted, and each lever is normally held in engaging position by a spring 23.

When a coin is dropped into a chute, the upper end of the lever is pressed outward, the lower end is pressed inward, and the plunger rod is released. It is to be understood that in the operation of the device a light pressure is exerted upon the plunger rod immediately prior to the insertion of the coin in the coin slot so that when the coin operates to release the lever 20 the plunger rod will be simultaneously operated to such an extent at least as to prevent relocking of the plunger rod as the initial downward movement of the plunger rod caused by the light pressure exerted thereon prior to and during the insertion of the coin prevents the return of the locking lever 20 to locking position.

Just above the partition 16, each chute is cut away, and a pair of channel shaped

leaves 24 and 25 is hinged to the chute at the cut away portion. One of these leaves 25 has a laterally extending arm 26 connected with mechanism to be later described, 5 while the other leaf 24 carries a cam lug 27. This cam lug 27 is normally just below a similar lug 28 on the adjacent plunger rod, and it will be evident that when the plunger rod is pressed downward the engagement of the cam lugs 27-28 will move 10 the leaves 24 and 25, with the coin between them laterally away from the plunger rod.

Referring to Figs. 2 and 3 it will be seen that the leaves 25 of the first two coin chutes 15 are connected by an arm 26 with one end of the lever 29 pivoted at 30 intermediate its end on the partition 16. The other end of each lever 29 engages a pin 31 on the bar 7 before mentioned. When these leaves 20 are moved laterally by the downward movement of the plunger, the bar 7 will be drawn to the left of Fig. 2, releasing the pawl 6, and releasing the turnstile.

The chutes 11, 12, and 13 are for permitting the payment of multiple fares, as for instance, five 5¢ fares, ten 5¢ fares, five 10¢ fares or the like.

In the multiple fare chutes, the leaves 25 are connected to bell cranks or elbow levers 30 32, the said levers being pivoted at 33 on the partition 16. A controlling shaft 34 is journaled substantially parallel with the bar 7, and an operating shaft 35 is journaled parallel with the shaft 34, between the same 35 and the bar 7. The shaft 34 has a bevel gear 36 at one end which meshes with a similar gear 37 on a short shaft 38 having a bevel gear 39 meshing with a gear 40 on the locking shaft 4 for the turnstile. This 40 shaft 34 also carries a series of pinions 41, the pinions corresponding in number to the number of the multiple fare coin chutes.

Each pinion 41 is adapted to be engaged by the teeth of a mutilated gear 42 loosely 45 mounted on the shaft 35, adjacent to the pinion 41. A ratchet wheel 43 is mounted on the shaft 35 adjacent to each mutilated gear 42, and one such ratchet wheel is secured to each mutilated gear. Each ratchet 50 wheel is engaged by a pawl 44 controlled by the adjacent bell crank 32.

When a multiple fare is paid, the movement of the leaves 24 and 25 laterally by the plunger will swing the bell crank adjacent thereto, and will advance the mutilated gear 42 to bring the teeth thereof into mesh with the pinion 41. A bevel gear 45 is rigid with each mutilated gear 42, and each bevel gear engages a bevel gear 46 on a shaft 47 55 journaled on the partition 16. Each of these shafts 47 carries a cam 48 at the end adjacent to the bar 7, and each cam engages a pin 49 on the bar.

When a mutilated pinion 42 is moved into 60 mesh with a pinion 41 as above mentioned,

the cam 48 adjacent thereto is also operated to move the locking bar 7 in a direction to release the pawl 6. The mutilated gears 42 are geared to the shaft 4 in such manner that the turnstile may turn for instance five 70 times, that is may turn to admit five passengers before the mutilated gear moves out of mesh with the pinion, and before the cam 48 releases the pawl controlling bar 7, to permit the pawl 6 to engage the teeth of the ring 5 to lock the turnstile controlling shaft. It will be obvious that only that cam 48 adjacent to the particular coin chute will operate, so that the release of the turnstile will continue during a predetermined number of turns of the turnstile. The movement of the cam is directly controlled by the turning of the turnstile. Referring to Fig. 2 the pawl 6 is returned into engagement with the teeth of the ratchet ring by a tail 85 50 having a pin 50^a which rides upon the teeth 51 arranged below the level of the teeth of the ring 5. This tail tends always to return the pawl to engaging position, when it is not held out of engagement by the locking bar. When any one of the cams 48 hold the bar 7 retracted, that is in such position as to hold the pawls 6 out of engagement with the teeth of the ratchet ring 5, the teeth 51 snap by the pin 50^a, this pin 50^a 90 being sufficiently resilient to permit of this action.

It is thus obvious that the master bar 7, pins 31 and levers 29, pins 49 and cams 48 and associated elements constitute release 100 mechanism for the lock mechanism and that the cams 48, their shafts 47 and pinions 46 constitute as a minor element of the release mechanism operating means for the cam. The pinions 36, 37 and 39, gears 41 and 42 and shafts 34, 35 and 38 constitute motion 105 transmission means between the turn stile and the operating means of the release mechanism.

Each coin chute delivers to a compartment 110 52 below the chute, and a gate or door 53 is arranged between each compartment 52 and the chute. These gates are normally held closed and are opened by the upward movement of the plunger when it is released. An angle bracket 54 is secured to each plunger below the partition 16, and each of these brackets is connected by an arm 55 with the shaft 56 to which the door or gate is also connected. These shafts 56 are journaled 115 in brackets 57 on the under face of the partition 16, when the plunger moves upward, the gate is opened to permit the coin to pass through the chute to the compartment 52. A glass front is provided for each compartment 52, in order that the motorman may observe the coins in the compartment.

Each compartment 52 delivers into a coin box 58 arranged directly below the compartment, and normally separated therefrom by 120 125 130

a gate or door 59. These gates are controlled by a lever 60 to dump the coins from the compartment 52 into the coin box, and the box may be removed at the barns for emptying. A counter is arranged adjacent to each plunger, and operated by the downward movement of the plunger to count the coins in the box. These counters may be of any usual or desired construction.

10 Referring to Fig. 1 it will be noticed that a turnstile is arranged at each end, the rear end being the entrance, while the front end is the exit. It will be obvious that entrance or exit may be at either or both ends. The 15 improved collector is designed to permit the services of a conductor to be dispensed with, and the turnstile may be at the entrance or exit, or the rear end may have a door which may be released by a spring operated by the 20 motorman-conductor. In the event of a panic, a master plunger is provided for releasing the pawl 6, the same being under the control of the motorman, and in practice this plunger will be so plainly designated, 25 that in case the motorman-conductor is disabled or killed any one else can release the door.

It will be understood that the turnstile has a sufficient number of bars to prevent persons passing through or over in the effort to leave the car by the entrance, instead of going to the exit door.

While any form of counter may be used, that shown in Figures 8, 9 and 10 is especially designed to be used, and is best adapted for the purpose, since it takes up but little space and requires slight power to operate.

The improved counter comprises a suitable 40 casing 65 in which is supported a shaft 66, the said shaft being supported by the rear wall of the casing and by a transverse partition 67 which is a dial in rear of the front wall of the case which, in practice, is transparent in order that the dial may be seen. This shaft carries toothed wheels 68, and 45 69, the former being of larger diameter than the latter.

The dial 67 is fixed in the casing, and a 50 bushing 70 is journaled in the dial, and the bushing carries on the opposite side of the dial 67 from the gear wheel a counting hand or indicator 71. A second counting hand or indicator 72 is secured to the shaft 66.

55 The counters are operated by the plungers 14, which have suitable projections for engaging the teeth of the wheel 68. Referring to Figure 10, it will be seen that the casing 65 has a slot 73, through which a roller 74 held on the plunger 14 may pass to engage the teeth of the wheel. The wheel is turned one tooth for each downward movement of the plunger, the said wheel being arranged 60 to count any suitable number, as, for instance, one hundred or any multiple thereof.

Each complete rotation of the wheel 68 is registered by the wheel 69, the said wheel 69 being moved a distance of one tooth at each complete rotation of the wheel 68.

A pawl 75 is mounted to slide radially of the wheel 68 and this pawl is normally spring pressed outward by a spring 76 held on the face of the wheel 68. This pawl has an angular portion which is adapted to engage the teeth of the wheel 69 and it is normally held out of engaging position with the said wheel by the spring 76. Once during each complete rotation of the wheel 68 the pawl 75 is engaged by a cam 77 held in the casing 65, and the pawl is depressed far enough to cause it to engage the teeth of the wheel 69. Thus the wheel 69 will be turned one tooth for each complete rotation of the wheel 68.

I claim:

1. A fare collecting device, comprising in combination with a turnstile, of means normally operative for locking the turnstile from turning movement in one direction, a series of coin controlled means for releasing the locking means, means operated by the turning of the turnstile and controlled by sundry of the coin controlled means to operative and inoperative position for holding the locking means released during a predetermined movement of the turnstile, the means for preventing rotation of the turnstile comprising a pawl and ratchet mechanism, a link connected with the pawl of the said mechanism, and having laterally extending stops, certain of the coin controlled means directly engaging stops of the link to move the same in a direction to release the pawl, cams engaging other of the stops, a shaft rotated by the turning of the turnstile, a second shaft having a driving connection with the cams and normally disconnected from the first named shaft, other of the said coin controlled means having means in connection therewith for connecting said last named shaft to the first named shaft.

2. In a device of the character described, a turn stile, locking mechanism for said turn stile, release mechanism for said locking mechanism including a master bar having a series of pins, operating means co-acting with said pins including a series of cams, actuating mechanism for said cams including a shaft and gearing, coin operated means controlling said actuating mechanism, motion transmission means between the turn stile and said cam operating means including a shaft, gears on said shaft and mutilated gears on said first-named shaft and adapted to be meshed with the gears on said last-named shaft under the control of said coin operated means.

3. In a device of the character described, a turn stile, locking mechanism for the

turn stile, release mechanism for said locking mechanism including a master bar having a series of pins, a series of cams co-operable with said pins, and operating mechanism for said cams, coin operated means controlling said release means and adapted to initially actuate the operating means for said cams, and motion transmission means between said turn stile and said cam operating means adapted to effect actuation of said cam operating means subsequent to the initial operation thereof by said coin operating means.

4. In a device of the character described, 15 a turnstile, locking mechanism therefor, release mechanism for said locking mechanism including a master bar having a series of pins projecting therefrom, a series of operating mechanisms coacting with said pins 20 and adapted to move and hold the master bar in released position for various predetermined periods, a series of coin operated mechanisms controlling the operating means

of the release mechanism and motion transmission means between the turn stile and 25 certain of the operating means of the release mechanism.

5. In a device of the character described, a turn stile, locking mechanism for said turn stile, release mechanism for said locking mechanism including a master bar, a series of operating mechanisms for said master bar adapted to hold the same in released position for variable times, coin operated mechanisms controlling said release 35 mechanisms, and motion transmission means between certain of the operating means of said release mechanism and said turn stile.

6. In a device of the character described, a turn stile, locking mechanism for the turn 40 stile, release mechanism for the locking mechanism including a master bar having a series of pins, a series of cams co-operable with the pins, and coin operated mechanism controlling said series of cams.

JOHN WESLEY POPE.
